UNITED STATES PATENT OFFICE.

PENELTON G. MIDGETT, OF DALLAS, TEXAS, ASSIGNOR OF ONE-HALF TO ROSSER THOMAS, OF DALLAS, TEXAS.

DRILL-BIT.

1,344,425.

Specification of Letters Patent. Patented June 22, 1920.

Application filed September 2, 1919. Serial No. 320,971.

To all whom it may concern:

Be it known that I, PENELTON G. MIDGETT, a citizen of the United States, residing at Dallas, in the county of Dallas and State of Texas, have invented certain new and useful Improvements in Drill-Bits, of which the following is a specification.

This invention relates to new and useful improvements in drill bit constructions.

10 The invention has particularly to do with drill bits such as are used in drilling wells, and the aim of the invention is to produce a bit which will be superior in many respects.

15 One of the particular features resides in a joint between the bit point and head whereby the point may be readily removed and others substituted; said joint involving liberal contacting surfaces between the point 20 and the head, and a locking arrangement whereby the parts are adequately secured together and ample contact therebetween in the direction of rotation, is had. Another salient point of the invention resides in the 25 provision of a lug and socket therefor which form part of the aforesaid joint and afford a positive connection between the head and the bit so that independent circumferential movement is precluded and rotation is transmitted to the point without lost motion.

30 A further feature resides in the disposition of cutting edges at a greater radial distance from the center than the remainder of the structure whereby ample clearance is given the bit.

35 The invention will be more readily understood from a reading of the following specification and by reference to the accompanying drawings, in which an example of 40 the invention is shown, and wherein:

Figure 1 is an elevation of a drill bit structure embodying the invention,

Fig. 2 is a reverse elevation of the parts shown in the Fig. 1,

45 Fig. 3 is an underside view of the structure,

Fig. 4 is a plan view of the same,

Fig. 5 is an elevation of the bit point at right angles to Fig. 1,

50 Fig. 6 is an elevation of the head corresponding in position to Fig. 5,

Fig. 7 is a cross-sectional detail on the line 7-7 of Fig. 1,

Fig. 8 is a sectional detail on the line 8-8 of Fig. 1, and

Fig. 9 is an end elevation of the head shown in Fig. 6.

In the drawings the numeral 10 designates a drill bit point and 11 a head connected thereto. The point is of the usual twist drill formation except that the cutting edges 12 have the greatest radial projection as will be apparent from observation of Fig. 3. The surface of the point is gradually cut back so as to reduce the diameter of the point toward the trailing edge 13. This construction gives the point liberal clearance, and a free cutting edge which will operate at its highest efficiency at all times. The point is shouldered at 14 and provided with a shank 15 of reduced diameter. It is obvious that the diameter or size of the bit may vary so long as it is greater than that of the shank which remains the same for all excessive sizes.

75 The purpose of making the point 10 and the head 11 separate is that an extremely hard and durable steel may be used for the point while the softer and less expensive metal may be utilized for the shank. The point is provided with an angular socket 16 extending radially in its upper end and also is provided with a boss 17, a shoulder 18 extending along one side of the socket and across the base of the boss; and also with a vertical contact face 19.

80 The head 11 is provided with a depending lug 20 angular in cross-section to snugly fit in the socket 16. The head is recessed at 21 and provided with an upright contact 85 face 22 positioned to engage the boss 17 as is shown in Figs. 1 and 7. The head also is recessed at 23 so as to provide an upright face 24 adjoining the face 19. By observing Fig. 7 it will be seen that the faces 22 and 24 are offset with relation to a connecting bolt 25 passing diametrically through the parts. In drilling the bit is revolved to the right and thus the head 11 through its lug 20 and its face 22 impart rotation to the 100 point, the contacting faces and surfaces in the line of rotation being very liberal as is apparent.

105 The connecting bolt has its head countersunk in a recess 26 in the boss 17 and its screw-threaded end is engaged in the head

15. The bolt has a circumferential groove 27 near its head. A lag bolt 28 is passed through the boss 17 at right angles to the bolt 25 so as to engage in the groove 27 and lock said bolt in place. This lag bolt has its screw-threaded end engaged in the head 11. On the opposite side a lag bolt 29 is passed through the shank 15 and has its screw-threaded end engaged in the head 11. It will be seen that all of the bolts have their screw-threaded ends engaging in the head which is of the softer metal and may be readily threaded, and this precludes the making of screw-threads in the hard metal 15 of the point. The bolts fasten the point and head together and by removing the same the head and bit may be easily separated. The usual water ducts 30 are provided in the head for supplying water to 20 the point.

What I claim, is:

In a drilling bit structure, a bit-point

having a rear portion, said rear portion embodying a boss and a recess arranged in end to end relation and having parallel side walls, said recess having a bottom wall provided with an angular socket, a head having a forward portion which embodies a boss and a recess arranged in end to end relation and having their side walls parallel, said bosses fitting in the recesses and disposed in end to end relation with their inner ends contacting, the boss of the bit-point having a smooth opening and the boss of the head having a screw-threaded opening which are 35 adapted to be in alinement, an angular lug carried by the free end of the boss of the head and adapted for insertion within the angular socket, and a screw passing through the smooth opening and engaging in the 40 screw-threaded opening.

In testimony whereof I affix my signature.

PENELTON G. MIDGETT.
